UNITED STATES PATENT OFFICE

124,303

DESIGN FOR A FLOWER RACK OR THE LIKE

Myrtle Irene Rennie Cheatham, Lockhart, Tex.

Application September 27, 1940, Serial No. 95,445

Term of patent 7 years

To all whom it may concern:

Be it known that I, Myrtle Irene Rennie Cheatham, a citizen of the United States, residing at Lockhart, in the county of Caldwell and State of Texas, have invented a new, original, and ornamental Design for a Flower Rack or the like, of which the following is a specification, reference being had to the accompanying drawing forming part thereof, in which:

Fig. 1 is a front elevational view of the flower rack showing my new design; and

Fig. 2 is a side elevational view of the rack shown in Fig. 1.

I claim:

The ornamental design for a flower rack or the like, as shown.

MYRTLE IRENE RENNIE CHEATHAM.
